UNITED STATES PATENT OFFICE

141,503

DESIGN FOR A TRAY

Carl G. Preis, Forest Hills, N. Y.

Application July 28, 1944, Serial No. 114,606

Term of patent 14 years

(Cl. D44—10)

To the Commissioner of Patents:

Be it known that I, Carl G. Preis, a citizen of the United States of America, residing at 60 Greenway South, Forest Hills, in the county of Queens and State of New York, have invented a new, original, and ornamental Design for a Tray, of which the following is a specification, reference being had to the accompanying drawing, forming a part thereof.

Fig. 2 is a top plan view of the tray shown in Fig. 1.

Fig. 3 is a side view of the tray shown broken away for convenience of illustration.

The characteristic feature of the design resides in a tray of the configuration, proportions and arrangement of the parts substantially as shown.

I claim:

The ornamental design for a tray, as shown and described.

CARL G. PREIS.
